UNITED STATES PATENT OFFICE.

SAMUEL SEGAL, OF NEW YORK, N. Y., ASSIGNOR TO SEGAL LOCK & HARDWARE CO.,
INC., OF NEW YORK, N. Y., A CORPORATION OF NEW YORK.

KEY-DUPLICATING MACHINE.

1,307,378.

Specification of Letters Patent. Patented June 24, 1919.

Application filed September 21, 1918. Serial No. 255,033.

To all whom it may concern:

Be it known that I, SAMUEL SEGAL, a citizen of the United States, and a resident of New York, in the county of New York and State of New York, have invented certain new and useful Improvements in Key-Duplicating Machines, of which the following is a specification.

My invention relates to key-duplicating machines and more particularly to machines for duplicating keys for cylinder locks such as the well known Yale or similar type lock keys.

The object of my invention is the production of a key-duplicating machine of simplicity of construction and operation which shall effectively, expeditiously and accurately produce a key similar to any given master or pattern key and which shall be adapted to fit and operate the same lock as the master or pattern key.

A further object of my invention is the production of a novel form of work-holding clamp which shall be made of a single integral piece of material and which shall be adapted to grip and firmly hold the master key and key blank during the cutting operation.

Other and further objects of the invention will appear from the following description, the invention consisting in the novel parts and combinations of parts hereinafter more particularly described and then specified in the claims.

In the accompanying drawings:

Figure 1 is a plan view of my improved key-duplicating machine showing the carriage with its work-holding clamps swung up manually to bring the master key and key blank in operative position.

Fig. 2 is a vertical cross-section on the line 2—2 Fig. 1 showing the work-holding clamps in operative position in dotted lines and in inoperative position, with my improved key-positioning gage coöperating with one of them, in full lines.

Fig. 3 is a front elevation of my improved machine on the line 3—3 of Fig. 2.

Fig. 4 is a vertical cross-section on the line 4—4 of Fig. 5. 50

Fig. 5 is a front elevation of my improved key-positioning gage showing it holding a key blank in the proper position before the same is transferred to the work-holding clamp of the machine. 55

Fig. 6 is a perspective view of the major part of the key-positioning gage.

Fig. 7 is an end elevation of the key-positioning gage.

Fig. 8 is a side elevation (partly in section) of the barrel of a conventional form of cylinder lock. 60

Fig. 9 is a vertical cross-section on the line 9—9 of Fig. 8.

In the key-duplicating machines of which I have knowledge it is the common practice, irrespective of the operation and construction of the cutting tool and guiding finger, to provide two clamps, identical in construction and size, one being adapted to hold the 65 clamp the master or pattern key and the other the key blank. The master key and key blank are usually positioned in their respective clamps by having their back or rear edges abut against or engage a stop 70 or flange on the clamps each of which occupies the same relative position on both clamps, and by also having the shoulder of the key adjacent the back or rear edge engage a fixed projection or stop on each 75 clamp. Thus the back edge of the key and the shoulder adjacent the back edge have been made the determining factors for properly positioning the key and blank in the clamps. It is apparent, however, that when 80 a key is inserted in a cylinder lock it is neither the back edge or the shoulder adjacent the back edge which determines the position of the key in the lock, but it is rather either of the grooves cut in the sides 85 of the key, as well as the shoulder adjacent the biting edge thereof, which determines its position for the reason that these grooves receive the fixed guides in the barrel of the lock and the shoulder adjacent the biting 90 edge engages the front face of the cylinder.

95

If these factors therefore are made the determining ones for properly positioning the key and blank in the clamps, as they are according to my invention, there can be no doubt but that the duplicated key will properly fit the same lock as the master key.

In Fig. 8 I have shown the barrel of a conventional cylinder lock at 1 said barrel usually having a slot 2 cut in the bottom thereof through which the rear or back edge of the key very often extends and with which the shoulder 3 adjacent the rear edge is in alinement but which shoulder does not engage any part of the barrel or lock. The back edge and shoulder adjacent the back edge in no wise determine the position of the key in the lock and when these factors are made the determining ones for positioning the master key and blank in their respective clamps the duplicated key will very often not fit the lock, one reason being that the stock of the key blank adjacent its back edge very often varies in width.

In Fig. 9, 4 indicates the usual guides of the lock adapted to enter the grooves cut in the sides of the key so that one or both of said grooves are determining factors as concerns the vertical position of the key in the lock while, as regards its horizontal position, this is determined by the shoulder 4 which engages the face of the barrel 1.

Having in mind, therefore, that the grooves in the sides of a key and the shoulder adjacent its biting edge determine the proper position of a key in its lock and that these factors are really the ones which should be taken into account when it is desired to properly position the master key and key blank in their respective clamps, I will proceed to describe my invention as illustrated in Figs. 1 to 7 inclusive wherein:

10 indicates the base of my improved key-duplicating machine which is provided with a body portion 11 having side plates 45 carrying rod 13, which connects the same. The carriage of the machine which is horizontally slidably mounted on rod 13, is indicated at 14 and is provided with arms 15 and one-piece work-holding clamps 16 and 16'. The upper portions or heads of said clamps are preferably enlarged and have slots 17 cut therethrough, forming two flat opposed surfaces or jaws adapted to engage the key to be clamped. For drawing together the two flat opposed surfaces or jaws of the heads of said clamps 16 and 16' into clamping position, I have provided suitable screw-threaded bolts 18 extending through the clamps and adapted to be turned or operated by winged nuts 19. The heads of said clamps are also provided with transverse slots 20 cut therein for a certain distance for a purpose to be presently described. The said clamps 16 and 16' are

identical in size and construction and being of one-piece are more simple in construction and more easily manufactured than other clamps of which I have knowledge. They are drawn together by the bolts 18 as previously described and automatically return to unclamping position when the bolts are unscrewed or untightened due to the spring action in the metal of the clamps.

My improved key-positioning gage comprises a major member 21 and a minor member 22 of equal height and width detachably held together by a screw-threaded bolt 23 passing therethrough, having an operating thumb-nut 24 on its end. The said screw-threaded bolt 23 carries a spring 24' fitting in a recess in the major portion 21, said spring 24' tending by its action to force said major and minor members apart. A slot 25 is cut in the lower portion of the body of both the major and minor members, said slot being adapted to receive the rib 26 formed by the transverse slots 20 in the heads of the work-holding clamps and the width of the gage is such that the lower parts of the major and minor members adjacent the slot 25 will also fit within the slots 20. The major member 21 is provided with a transverse slot 27 in its inner face adjacent the lower end thereof and with teeth 28 adapted to engage the groove on either side of the key. 29 indicates a U-shaped piece adapted to fit snugly around three sides of the positioning gage to prevent a rotary movement of either the major or minor member with respect to the other. Said U-shaped piece is provided with a slot 30 in the rear wall thereof through which the screw-threaded bolt 23 extends and 31 indicates an ordinary washer interposed between the U-shaped piece and the thumb-nut 24. Obviously by means of the slot 30 the U-shaped piece 29 is capable of a vertical movement on the positioning gage and it may be locked in any desired position by a tightening of the thumb-nut 24.

To properly position the key in its work-holding clamp 16 it is placed in the positioning gage between the major member 21 and the minor member 22 with its biting edge 32 (see Fig. 5) facing upwardly and with the teeth 28 entering the groove 34 of the key. The U-shaped piece 29 is then raised or lowered to the proper position and the shoulder 33 of the key is pushed into engagement therewith, after which the thumb-nut 24 is tightened and the key is firmly held in the desired position. To transfer the key in this position to the clamp 16, the jaws of the clamp are opened and the gage is mounted therein with the rib 26 of the clamp entering the slot 25 of the gage and the bottom por-

tions of the gage adjacent the slot 25 entering the slots 20 of the clamp. The clamp is then tightened by means of the winged nut 19 so that the jaws thereof grip the key adjacent its back or rear edge, after which the gage is removed by unloosening the thumb-nut 24. The key blank is then positioned and held in the clamp 16' in the identical manner.

10 35 indicates a pivoted spring-pressed guiding finger suitably mounted in a post 36 extending upwardly from the body of the machine. 37 indicates a standard having a shaft journaled therein which carries a rotary cutting tool 38 removably mounted thereon and held in position by a nut 39. Keyed to the other end of the shaft is a driving wheel 40 provided with a suitable groove adapted to receive a belt and having a handle 20 41 so that the cutting tool may be rotated either by hand or it may be power driven.

The duplicating operation is as follows:

After the master key and key blank have been properly positioned in their respective 25 clamps, the cutting tool 38 is rotated and the carriage 14 with its clamps is swung up manually on the rod 13 to cause either end of the biting edge of the master key to be pressed against the guiding finger 35 against the action of its spring. The carriage is moved slowly and horizontally along the rod 13, the master key at all times being kept in engagement with the guiding finger. The forward movement of the carriage toward 30 35 the guiding finger is limited by the depth of each indentation or cut in the master key and an indentation or cut of equal depth will be made in the key blank by the cutting tool 38 as will be obvious. Both clamps 16, 16' 40 being rigidly secured to the carriage 14 move together by manually engaging either one of them. If desired a wood or other bar (not shown) may be threaded longitudinally through the holes 50 in the clamps 16, 16' to 45 form a pressure bar for the hand of the operator to manipulate the carriage 14.

What I claim as my invention is:

1. In a key-duplicating machine, a carriage and work-holding clamps for clamping the master key and key blank and comprising one-piece split rings secured to said carriage, said clamps being provided with means for forcing the same into clamping position.

55 2. In a key-duplicating machine, a carriage slidably mounted on the machine and work-holding clamps for clamping the master key and key blank and comprising one-piece split rings integral with said carriage, said clamps being provided with means for forcing the same into clamping position.

60 3. In a key-duplicating machine, a work-holding clamp secured to the machine and comprising a one-piece ring with a slot cut

therethrough having flat opposed surfaces 65 and means for drawing together the parts of the clamp adjacent the slot to clamp a key therebetween.

4. In a key-duplicating machine, a pair of work-holding clamps for holding and clamp- 70 ing the master key and key blank and a removable positioning gage adapted to coöperate with said work-holding clamps and to position the master key and key blank be- 75 tween the same in the same relative position and in a position determined by a groove in the side of the keys and the shoulder adjacent the biting edge thereof.

5. In a key-duplicating machine, a pair of work-holding clamps for holding and 80 clamping the master key and key blank and having flat opposed surfaces and slots cut transversely across the top thereof and a removable gage adapted to position the master key and key blank between the flat op- 85 posed surfaces of said clamps and being also adapted to fit within said slots.

6. In a key-duplicating machine, a pair of clamps therefor adapted to hold and clamp a master key and key blank and a removable 90 positioning gage adapted to coöperate with said jaws and comprising a major and minor member removably held together and adapted to hold the master key or key blank there- 95 between by engagement of the groove in one side of the master key or key blank and the flat face of the opposite side.

7. In a key-duplicating machine, a pair of clamps therefor and a removable gage adapted to coöperate with said clamps and 100 position a master key and key blank between the jaws thereof and comprising a major member and a minor member adapted to hold the master key or key blank there- 105 between and having means for preventing a returning movement of one member with respect to the other.

8. In a key-duplicating machine, a pair of clamps therefor and a removable gage adapted to coöperate with said clamps and 110 to position a master key and key blank between the jaws thereof and comprising a major member and a minor member adapted to hold the master key or key blank there- 115 between by engagement of a flat side of the master key or key blank and a groove in the reverse side thereof and means for preventing a turning movement of one member with respect to the other, said means also acting as a stop for the shoulder of the master key or key blank adjacent its biting edge.

9. In a key-duplicating machine, a pair of clamps therefor and a removable gage adapted to coöperate with said clamps and 120 to position a master key and a key blank be- 125 tween the jaws thereof and comprising a major member and a minor member removably held together and adapted to hold the

master key or key blank therebetween by engagement of a flat side of the master key or key blank and a groove on the reverse side thereof, a U-shaped piece engaging three sides of said gage and adapted to prevent a turning movement of one member with respect to the other and acting as a stop for the shoulder of the master key or key blank adjacent its biting edge, said U-shaped piece

being also capable of a vertical sliding movement on said gage.

Signed at New York, in the county of New York and State of New York, this 20th day of September, A. D. 1918.

SAMUEL SEGAL.
